UNITED STATES PATENT OFFICE.

THOMAS J. PARKINSON, OF PITTSBURG, PENNSYLVANIA.

CURTAIN-FIXTURE.

SPECIFICATION forming part of Letters Patent No. 296,048, dated April 1, 1884.

Application filed December 29, 1883. (No model.)

To all whom it may concern:

Be it known that I, THOMAS J. PARKINSON, of Pittsburgh, in the county of Allegheny and State of Pennsylvania, have invented certain new and useful Improvements in Curtain-Fixtures; and I do hereby declare that the following is a full, clear, and exact description of the invention, which will enable others skilled in the art to which it appertains to make and use 5 the same, reference being had to the accompanying drawings, which form a part of this specification, in which—

Figure 1 is a front elevation of my improved fixture, the curtain-cord being indicated by 15 dotted lines. Fig. 2 is a side view of same.

This invention relates to the construction of that class of devices in curtain-fixtures intended to be used for adjusting the tension of the operating-cord; and it consists in the novel 20 construction and combination of parts, substantially as hereinafter fully described and claimed.

In the drawings, A designates a plate having two holes in it for the screws b and c, where- 25 by it is secured to the window-frame and there held in a rigid position. Along one edge of plate A is a raised rim, d, serrated with ratchet-teeth, as shown. Rim d is, by preference, an arc of a circle, but may, when desired, be 30 straight. The screw c is first inserted in place and driven. Screw b is then applied, after being inserted through the eye e of the lever B. Screw c holds plate A tightly against the wood-work of the window, and screw b prevents it 35 from rotation and acts as pivot for lever B. The lever B is made in one piece, having the cord-knob i and the knife-edge k undercut, as

shown. Knife-edge k engages automatically with the ratchet-rim d. Lever B is rigid, and is adapted to have slight play on its pivot b, 40 so that when the strain of the cord h is on it the tendency is to rock the knife-edge k into deeper and more secure engagement with the ratchet d. The cord h is slipped onto the 45 grooved knob i, and tightened by simply drawing the lever B downwardly. The strain of the cord always compels the edge k to engage the ratchet, and hence there is no tendency to slip. The lever B being rigid, there is no tendency to yield outwardly.

The device may be also applied to awning-ropes, when constructed on a suitable scale.

Where the rim d is made straight instead of arc-shaped, obviously the teeth on the rim will be given radial form, their edges pointing toward a common center. In such case the knife-edge of the lever would be somewhat longer, 55 so as to reach all the teeth.

I claim as my invention—

The described cord-tightener, consisting of 60 the perforated plate A, having ratchet-rim d raised upon its front, rigid lever B, having eye e, grooved knob i, and undercut knife-edge k, and pivot-screw b, said lever B adapted to a slight rocking motion on its pivot, substan- 65 tially as described.

In testimony that I claim the foregoing as my own I have hereto affixed my signature in presence of two witnesses.

THOMAS J. PARKINSON.
